UNITED STATES PATENT OFFICE.

DAVID D. EVANS, OF RACINE, WISCONSIN.

PRESS-GUARD.

1,179,816.

specification of Letters Patent. Patented Apr. 18, 1916.

Application filed April 9, 1913. Serial No. 759,964.

To all whom it may concern:

Be it known that I, DAVID D. EVANS, a citizen of the United States, and resident of Racine, in the county of Racine and State of Wisconsin, have invented new and useful Improvements in Press-Guards, of which the following is a description, reference being had to the accompanying drawings, which are a part of this specification.

10 This invention has for its object to provide a guard member for power operated punch presses which will serve to prevent the operator leaving his hand beneath the punch when the press is started in operation

15 and thus constitute a safety device to avoid injury to the operator's hands which so frequently results with unprotected punch presses of ordinary construction.

The invention consists of a guard arm 20 pivotally mounted on a stationary bracket support on the guide of the punch head and having an actuating connection with the press head comprising a slot in which travels a pin or stud projecting from the punch head so that the downward movement of the punch head gives the guard arm a swinging movement carrying its lower end across the face of the press or the die space beneath the press head and sweeping the hand 25 30 of the operator therefrom if it has not been previously removed.

With the above and other objects in view the invention consists in the press guard as herein claimed and all equivalents.

35 Referring to the accompanying drawings in which like characters of reference indicate the same parts in different views: Figure 1 is a front elevation of a portion of a punch press having the press guard of this 40 invention applied thereto; Fig. 2 is a sectional plan view thereof.

In these drawings 10 indicates the press head or cross head which carries the punch or die member 11 and which reciprocates 45 vertically and co-operates with a lower punch or die not shown. The press head is guided in its movements between the guide members 12 secured to the frame 13 on either side of the press head 10, all of which is 50 usual construction with punch presses. A bracket 14 is secured to the frame and projects forwardly beyond the plane of the front of the press head to form a rigid stationary support for a bracket extension arm 55 15 which has pivotally mounted at its end a slotted plate 16, the pivotal connection

17 of said plate being located at one end thereof and the slot 18 extending from near the pivotal connection to the other end of the plate. A guard arm 19 is detachably secured to the plate 16 and together they constitute a guard member or a substantially vertical lever and a stud 20 is threaded into the press head 10 and carries a roller 21 which projects through the slot 18 of the plate to form 60 65 an actuating connection therewith. The position of the stud on the press head is such that it travels past the pivotal connection 17 just before reaching the upper end of the stroke of the press head whereby the downward movement of the press head causes the stud to pass the pivotal connection 17 at the beginning of the movement. The slot 18 is preferably straight for the greater portion of its length and the straight portion thereof is not directed toward the pivotal connection, or the line of its direction would pass a slight distance from the pivotal connection but the inner end of the slot is curved or angular and directed toward the 70 75 80 85 90 95 100 105 pivotal connection as clearly seen in Fig. 1, forming a hump or shoulder 22 at the bend thereof which is the principal point of engagement for the roller 21 in its travel from one end of the slot to the other. It is said to be the principal point of engagement for the roller for the reason that the roller remains in engagement with this point longer than with any other during its downward travel and while in engagement with this point the roller in its downward movement causes the guard arm 19 to swing from the position shown in full lines in Fig. 1 to the position shown in dotted lines. When the arm 19 reaches the position shown in dotted lines the roller travels through the straight portion of the slot without further affecting the position of the guard arm, but in the return or upward movement of the roller after traveling through the straight portion of the slot without affecting the position of the swinging arm, it meets with the angular portion of the slot and returns the swinging guard arm to the position shown in full lines.

The movement of the guard arm 19 from the one position to the other as described at the beginning of the downward movement of the press head causes the lower end of said arm to swing quickly across the front 110 of the die space beneath the press head or what may be termed the face of the press

and push the hand of the operator from beneath the punch so as to avoid injury if he is careless about removing his hand at the proper time. The guard arm 19 is made detachable from the plate 16 to permit of an arm being used suitable to the die space of the press, arms of various lengths being interchangeable for this purpose. The connection between the bracket 14 and the extension arm 15 is an adjustable connection with bolts fitting in slots to permit of the bracket extension being adjusted in order to suit the requirements of different punch presses.

15 What I claim as new and desire to secure by Letters Patent is:

1. A press guard, comprising a bracket adapted for connection with the frame of a press, a slotted plate pivotally mounted on the bracket, a guard arm carried by the slotted plate, and a stud adapted for connection with the press head and traveling in the slot of the plate for causing the guard arm to swing across the front of the die space at the beginning of the downward movement of the press head.

2. A press guard, comprising a bracket adapted for connection with a press frame, an extension arm adjustably mounted on the

bracket, an angularly slotted plate pivotally mounted on the end of the extension arm, a guard arm attached to the plate, a stud adapted for connection with the press head, and a roller on the stud traveling through the angular slot of the plate for causing a quick swinging movement of the guard arm across the front of the die space at the beginning of the downward movement of the press head.

3. The combination with a press, of a safety device, the said press having a frame, a die fixed on the frame and a punch co-acting with the said die and mounted to reciprocate in the said frame, and the said safety device having a vertically disposed lever fulcrumed on the front of the said frame, the lower portion of the said lever being adapted to move across the front of the die and punch, and the upper portion having an angular slot and a stud on the cross head of the punch engaging the said slot.

In testimony whereof, I affix my signature, in presence of two witnesses.

DAVID D. EVANS.
